United States Patent Office

Des. 198,602
Patented July 7, 1964

198,602

CAMERA

Dennis A. Burgess, Minneapolis, Minn., assignor to Precision Camera, Inc., Minneapolis, Minn., a corporation of Minnesota

Filed Dec. 18, 1963, Ser. No. 77,855

Term of patent 14 years

(Cl. D61—1)

FIG. 1 is a front perspective view of a camera showing my new design;

FIG. 2 is a rear perspective view thereof;

FIG. 3 is an elevational view of the side shown in FIG. 1;

FIG. 4 is a top plan view of the camera;

FIG. 5 is a front elevational view thereof;

FIG. 6 is an elevational view of the side shown in FIG. 2; and

FIG. 7 is a rear elevational view of the camera.

I claim:

The ornamental design for a camera, substantially as shown.
